[57] **CLAIM**

The ornamental design for a handle for an endoscopic surgical instrument, as shown and described.

DESCRIPTION

FIG. 1 is a front elevational view of a handle for an endoscopic surgical instrument showing our new design, shown in closed position, the rear elevational view being a mirror image thereto;

FIG. 2 is a bottom plan view thereof;

FIG. 3 is a top plan view thereof;

FIG. 4 is a front elevational view thereof, shown in open position, the rear elevational view being a mirror image thereto;

FIG. 5 is an end elevational view thereof; and,

FIG. 6 is an end elevational view thereof, opposite that shown in FIG. 5.

The design of the endoscopic surgical apparatus is embodied in the handle portion shown in full lines in FIGS. 1-7. The portions of the instruments shown in broken lines do not constitute a part of the ornamental design.

The broken line showing of the tips in the FIGS. 1 through 4 is for illustrative purposes only and forms no part of the claimed design.
